LUMINAIRE

Myron F. Pettengill, Hendersonville, N.C., assignor to
General Electric Company, a corporation of New York

Filed Nov. 24, 1961, Ser. No. 67,668

Term of patent 14 years

(Cl. D48—31)

FIG. 1 is an elevational view of a luminaire showing my new design;

FIG. 2 is a top plan view; and

FIG. 3 is a bottom plan view thereof.

I claim:

The ornamental design for a luminaire, as shown.
